UNITED STATES PATENT OFFICE

NICHOLAS J. WALSH, OF SCHENECTADY, NEW YORK, ASSIGNOR TO WEBER ELECTRIC COMPANY, OF SCHENECTADY, NEW YORK, A CORPORATION OF NEW YORK

DESIGN FOR A SWITCH COVER

Application filed July 15, 1931. Serial No. 40,562. Term of patent 14 years.

To all whom it may concern:

Be it known that I, NICHOLAS J. WALSH, a citizen of the United States, residing at Schenectady, county of Schenectady, State of New York, have invented a new, original, and ornamental Design for Switch Cover, of which the following is a specification, reference being had to the accompanying drawings forming a part thereof.

Figure 1 is a perspective view, Figure 2 is a front elevational view, and Figure 3 is a side elevational view, showing my new design.

I claim:

The ornamental design for a switch cover, substantially as shown.

NICHOLAS J. WALSH.
